UNITED STATES PATENT OFFICE.

LUCIEN DEVAUX, OF PARIS, FRANCE, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 9, 1923. Serial No. 667,470.

To all whom it may concern:

Be it known that I, LUCIEN DEVAUX, a citizen of the Republic of France, residing at Paris, in the Republic of France, have 5 invented certain new and useful Improvements in Telephone-Exchange Systems, of which the following is a full, clear, concise, and exact description.

This invention relates to telephone exchange systems and more particularly to 10 such systems as are adapted to provide service in a private branch exchange.

Systems of this character are usually arranged so that the apparatus of the private 15 branch exchange may obtain connection with apparatus local to the exchange and is also enabled to obtain connection with a line leading to the main exchange to the exclusion of other apparatus.

20 It is the object of this invention to provide an improved system of this character. The invention will be more fully understood from the following description taken in connection with the accompanying drawings, Figs. 1 and 2 of which when taken 25 together with Fig. 2 beneath Fig. 1, illustrating a system in accordance with the invention.

Each subscriber's substation, two of which 30 are disclosed in Fig. 1 of the drawings, is provided with the usual switchhook, receiver, transmitter, condenser, bell and induction coil connected in the well known manner. Further, each station is provided 35 with a pair of keys 103 and 104 and an earth connection, the object of the keys being to connect earth to either of the conductors of the subscriber's line. Each subscriber's line leading to the exchange apparatus consists of two conductors only with 40 a connection to ground at the substation and has associated with it three line relays. These line relays are indicated at 105, 106 and 107. Each subscriber's line extends through 45 the back contacts of relay 105 to a key, such as, 221, located upon the operator's keyboard through which key the subscriber's line may be connected to other subscribers' lines in the exchange or to a trunk circuit extending 50 ing to the main exchange.

Only one trunk circuit 101, 102 has been disclosed extending from the private branch exchange to the main exchange indicated in the left portion of Fig. 1, but it is obvious 55 that additional trunk circuits with cor-

responding equipment may be added, as the traffic between the branch exchange and the main exchange requires. The private branch exchange monitor's head set is shown in the lower right corner of Fig. 2 and may be connected to a subscriber's line of the private branch exchange through a key, such as, 220 or to the trunk line 101, 102 extending to the main exchange by key 260. It is thought that the invention may be more 60 fully understood from the following description of the operation of the circuits disclosed.

It will be assumed first that the subscriber A desires to establish a local connection to the subscriber B at the same private branch exchange. The subscriber A removes his receiver which closes the substation loop across his line in the usual manner. The subscriber thereupon presses the key 104, which operation opens contact 110 and closes contact 111. The operation of depressing key 4 also permits the lower portion of the locking lug 112 to move into engagement with the lower moving spring 70 of the key so that the contact 111 remains locked in its closed position for a short time after the key 104 is released by the subscriber. Contact 110, however, closes, as soon as the key 104 is released so that for 75 an instant both contacts 110 and 111 are closed. When the key 104 has attained its uppermost position, the locking lug is forced away from the lower moving spring and contact 111 is again opened. The depression 80 of the key 4 closes a circuit for relay 107 which may be traced from battery through the winding of this relay, the right armature and back contact of relay 106, the innermost left normal contact key 220, the 85 inner left normal contact of key 221, the inner right armature and back contact of relay 105, upper contact of key 103 in its normal position, through the substation 90 loop, contact 111 of key 104 to ground. Relay 107 energizes, closing a locking circuit which may be traced as previously described through the subscriber's substation 95 loop and thence over contact 110 as soon as key 104 reaches its normal position, the outer right armature and back contact of relay 105, the inner right normal contact 100 of key 221, the inner right normal contact of key 220 and thence to ground at the left armature and front contact of relay 107. 105 110

- Relay 107 at its right armature contact closes a circuit for relay 222 which in turn establishes an obvious circuit for the call signal 254.
- 5 The monitor at the private branch exchange upon noticing the operation of the call signal 254 depresses key 220 associated with the calling subscriber's line A. This operation connects the subscriber's line A 70 through the innermost springs and alternate contacts of key 220, the left and right inner normal contacts of key 221 to conductors 223 and 224 which are connected to the monitor's head set. In addition, the subscriber's line is connected over the left and right intermediate springs and alternate contacts of key 220 through the windings of battery feed coil 225 to battery and ground, whereby the calling line and the monitor's 80 head set are supplied with talking current. The monitor then communicates with the subscriber A and ascertains the number desired. It having been assumed that the subscriber A desires to communicate with subscriber B, the monitor depresses key 221 so as to connect the line of the calling subscriber to the conductors 226 and 227. This connection is established over the innermost springs and front contacts of key 221, the 85 circuit previously traced from the subscriber's line to the monitor's head set being at the same time broken at the inner normal contacts of key 221. The monitor having depressed key 221, releases key 220. Talking current is supplied to the calling subscriber's line over the inner springs of key 221, through the left and right intermediate springs and normal contacts of key 229 and the windings of battery feed coil 228. Since 90 relay 230 is included in series with conductors 227 between the springs of key 221 and the battery feed coil 228, relay 230 becomes energized over the subscriber's line A but performs no useful function at this time.
- 40 45 The monitor now throws key 231 associated with the wanted subscriber's line B and operates the magneto 232 to call the subscriber. Current from the magneto flows over conductor 223 the inner left spring and alternate contact of key 231, the normal contacts of the inner left spring of key 233, the inner right armature and back contact of relay 105', the upper contact of key 103' and thence through the call bell of substation B, contact 110', the outer right armature and back contact of relay 105', the normal contacts of the inner right spring of key 233, the inner right spring and alternate contact of key 231, conductor 224, thence back to the magneto 232. The subscriber B upon 100 hearing the call signal removes his receiver from the switchhook and the monitor upon hearing the response of the called subscriber depresses key 233 so as to connect the subscriber's line B directly with conductors 226 and 227. The monitor then releases key 231. The two subscribers A and B may now converse over the interconnecting link circuit 226, 227 both being supplied with talking current through the battery feed coil 228. 70 So long as either subscriber retains his receiver off its switchhook, relay 230 is maintained energized. When, however, both subscribers have restored their receivers to their switchhooks, relay 230 deenergizes and closes 75 a circuit from ground through its armature and back contact, the outer left alternate contact of key 221 to battery through the relay 222 causing the operation of signal 254 and a second circuit in parallel therewith extending through the outer left alternate contact of key 233 to battery through the relay 234 which, in turn, causes the operation of signal 245. The monitor upon noticing the operation of these signals, releases the keys 221 and 233 thereby disconnecting the two subscriber's lines from link conductors 226 and 227.
- 50 It will now be assumed that a subscriber, such as subscriber A, of the private branch exchange desires to establish a connection with the trunk circuit 101, 102 extending to the main exchange. For this purpose the exchange circuit is taken into use by the subscriber A to the exclusion of other subscribers of the private branch exchange. 90
- 55 It is to be remarked that battery 155 of the private branch is permanently charged when the exchange line is idle from battery 156 at the main exchange over conductor 101, the circuit being as follows: Battery 156, resistance lamp 152, back contact of relay 148, conductor 101, outer right armature and back contact of relay 142, retardation coil 157, inner armature and back contact 105 of relay 145 and through the battery 155 to ground. The potential of battery 155 being lower than the potential of battery 156, current flows continuously from battery 156 to the battery 155 so long as relays 142 and 145 110 are deenergized.
- 60 65 The subscriber A to initiate a call to the main exchange, depresses the key 103 of the substation thereupon closing a circuit for relay 106 which may be traced from battery 156 through the winding of relay 140, right winding of relay 106, left armature and back contact of relay 107, inner right spring and normal contact of key 220, normal contacts of the inner right spring of key 221, outer right armature and back contact of relay 105, contact 110 of key 104, thence over the subscriber's line loop, contact 141 of key 103 to ground. Relay 106 thereupon energizes and closes at its left armature contact a locking circuit which is independent of contact 141 of key 103, the contact 141 opening as soon as the key 103 is entirely released. The locking circuit of relay 106 may be traced from ground through the left winding and 125
- 70 75 80 85 90 95 100 105 110 115 120 125 130
- 65 70 75 80 85 90 95 100 105 110 115 120 125 130

left armature contact of relay 106, the right winding of relay 105, inner right armature and back contact of relay 142 to battery at the outer left armature and back contact of relay 143. Relay 105 energizes in the locking circuit of relay 106, connecting the conductors of the subscriber's line over its right armatures and front contacts through the windings of relay 144 to the conductors 101 and 102 of the trunk circuit extending to the main exchange.

When the subscriber at substation A has been connected to the conductors 101 and 102 of the trunk circuit, current flows from battery 156 at the main exchange over trunk conductor 101, the left high resistance winding of relay 144, the inner right armature and front contact of relay 105 thence over the subscriber's line loop, returning over the outer right armature and front contact of relay 105, the right low resistance winding of relay 144, conductor 102 to ground to the winding of relay 147. Relay 147, upon energizing, in this circuit closes an obvious circuit for the signal 149 which thereupon glows, indicating to the main exchange operator that a call is incoming over the trunk circuit from the private branch exchange. The operator then responds by inserting plug 151 into the jack 150, whereupon the cut-off relay 148 is operated in the usual manner disconnecting relay 147 from the conductor 102 of the trunk line.

Relay 144 which also energized over the interoffice trunk circuit, closes a circuit extending from battery through its armature and front contact, the windings of relays 145 and 143, the left winding of relay 105 and left armature contact of this relay to ground. Relay 145, upon energizing, opens the connection between the main exchange battery 153 and the private branch exchange battery 155 at its inner armature and back contact and at the front contact of this armature establishes a locking circuit for itself and for relays 143 and 105 independent of relay 144. Relay 143, upon energizing, opens the initial energizing circuit of relay 105 at the outer left armature and back contact of relay 143 and also opens the locking circuit previously traced through the left winding of relay 106. Relay 106 thereupon deenergizes. At its inner left armature and front contact, relay 143 prepares a circuit for relay 158 which, however, is not operated until relay 144 becomes deenergized. At its right armature and front contact, relay 143 establishes an obvious circuit for relay 154 which, in turn, operates the signal 133 indicating to the branch exchange monitor that the interoffice trunk circuit is busy. At the outer armature contact of relay 145, a shunt is placed around the left high resistance winding of relay 144 for effecting a more efficient talking circuit be-

tween the subscriber's line and the main exchange. Relay 144 is, however, maintained energized so long as either the calling subscriber maintains his receiver off his switchhook or the exchange operator retains the plug 151 in the jack 150.

If the apparatus at the main exchange is of the automatic type it may be readily arranged that this apparatus may be operated under the control of a calling device installed at the substation of the subscriber in the branch exchange. It will be observed that the circuit of relays 145, 143 and 105 is closed independently of the contact of relay 144 so that if relay 144 vibrates in response to a calling dial on a branch exchange line when the subscriber dials the wanted line number, the opening of this contact does not cause the deenergization of relays 145, 143 and 105 and the consequent disconnection of the calling line from the interoffice trunk.

At the end of the conversation when the subscriber hangs up his receiver, current ceases to flow over the interoffice trunk line and relay 144 deenergizes, completing at its armature and back contact, the circuit of relay 158 which relay in turn short-circuits relay 145. This latter relay thereupon deenergizes and at its inner armature and front contact opens the previously traced locking circuit extending through the windings of relays 143 and 105. Relay 143, upon deenergizing, releases relay 154, discontinuing the busy signal 133 and also opens the circuit of relay 158. All relays employed in the establishment of the connection are now in their normal positions. At the main exchange the operator receives the usual disconnect signal and takes the plug 151 from the jack 150.

Should the monitor desire to call the main exchange, the interoffice trunk circuit being assumed free, the monitor will depress key 260 thereby closing the circuit of relay 142 which may be traced from battery through the right armature and back contact of relay 143, winding of relay 142, the outer right spring and normal contact of relay 229, the left intermediate spring and alternate contact of key 260 to ground. Relay 142 energizes and at its left armatures and front contacts connects the conductors 101 and 102 of the exchange trunk through alternate contacts and inner springs of key 260 to conductors 223 and 224 leading to the monitor's headset. Should, however, the exchange line be busy relay 143 will be energized and the energized condition of this relay will prevent the closure of the circuit of relay 142 so that the monitor's headset cannot be associated with the exchange line.

In order that the monitor may be apprised of the fact that the exchange line is busy, a circuit is established for the vibrating relay 140 extending from battery through the

winding of relay 140, the inner left armature and back contact of relay 142, the inner left spring and alternate contact of key 260, conductor 223, thence through the monitor's 5 headset, conductor 224, the inner right spring and alternate contact of key 260 to ground at the left armature and back contact of relay 142 through resistance 161. Relay 140 energizes in this circuit, short-circuiting 10 its own winding so that so long as the relay 142 remains deenergized, due to the busy condition of the interoffice trunk circuit, relay 140 intermittently operates thereby producing a tone in the receiver of the monitor's 15 headset.

Should another subscriber, such as the subscriber B, of the local exchange desire to call the exchange line when the latter is in use, as, for example, by the subscriber A, 20 the subscriber B will depress the button 104' of the substation set thereby causing the energization of relay 106' over a circuit similar to the circuit described for the energization of relay 106 associated with the 25 subscriber's line A. The relay 106' closes at its inner right armature a circuit extending from ground through the right winding and inner right armature of relay 106', the right winding of relay 105', the inner right 30 armature contact of relay 142 to the outer left armature of relay 143, but since the interoffice trunk has been assumed to be busy, relay 143 is at the time energized and the circuit of relay 105' cannot be completed. 35 Consequently, the subscriber's line B cannot be connected to the interoffice trunk circuit. Should the interoffice trunk line have been taken in use by the operator, the relay 142 will be at the time energized as previously described and the circuit of relay 105' cannot therefore be completed since it 40 is open at the inner right armature and contact of relay 142. In order that the subscriber B may be informed of the busy 45 condition of the interoffice trunk circuit, a circuit is established at this time from battery, through the winding of vibrating relay 140, the left winding of relay 106', left armature and back contact of relay 107', 50 inner right spring and normal contact of key 231, normal contacts of the inner right spring of key 233, outer right armature and back contact of relay 105' and thence over the substation loop of substation B, the inner right armature and back contact of relay 105', the normal contacts of the inner left spring of key 233, the inner left spring and normal contact of key 231, the outer 55 armature and front contact of relay 106' to ground at the normal contact of key 246. Relay 140, due to the fact that its armature short-circuits its winding upon each attraction thereof, vibrates producing a tone in the receiver of substation B. 60

65 When a call is incoming from the central

office, ringing current applied to the trunk conductors 101 and 102 passes through the left winding of ring up relay 262 which, upon energizing, locks in a circuit extending from battery through the intermediate 70 left spring and normal contact of key 260 to ground at the intermediate armature of relay 262. At its outer armature and front contact, relay 262 establishes an obvious circuit for signal 263 for signaling the branch 75 exchange monitor that a call is incoming. Relay 262 at its intermediate armature contact also establishes a circuit extending over the outer right spring and normal contact of key 229 through the winding of relay 80 142 to battery at the right armature and back contact of relay 143 for operating relay 142. Relay 142 immediately connects the conductors 101 and 102 of the interoffice 85 trunk over its left armatures and front contacts to contacts of key 260. Relay 142 also disconnects battery at its inner right armature and back contact for preventing the operation of a subscriber's line relay, such as 105, and the connection of a local 90 subscriber's substation to the interoffice trunk. Relay 262 also establishes a circuit over its inner right armature contact to battery through the call bell 244 to more particularly attract the private branch exchange monitor's attention to the fact that a call is incoming from the main office. In response to the operation of signal 263 and the ringing of bell 244, the monitor depresses key 260 completing the connection 95 from the interoffice trunk 101, 102 with conductors 223, 224 extending to her headset.

Assuming that subscriber A is wanted, the private branch exchange monitor rings up the subscriber by depressing the key 220 105 and operating the generator 232 in the manner previously described in connection with calling the subscriber B. The interoffice trunk line is held following the depression of key 220 by the retardation coil 259 which is connected across conductors 223 and 224 between the contacts of key 220 and key 260. When the subscriber A has answered, the monitor transfers the connection by depressing key 246. The depression of key 246 110 closes a circuit over the alternate contact of this key, the outer left spring and alternate contact of key 260, the winding of relay 163 to battery at the right armature and back contact of relay 143. At the same time, key 246 breaks the locking circuit extending through windings of relays 106, 106', etc., of the different subscribers' lines thus deenergizing any such relay which might at the time be in its operated position. Relay 163, upon energizing, closes a circuit which reestablishes the circuit of relay 105 broken at the back contact of relay 142 and which may be traced from battery, winding of relay 140, right winding of re- 115 120 125 130

lay 106, left armature and back contact of relay 107, outer right spring and alternate contact of key 220 to ground at the right armature and contact of relay 163. Relay 5 106 energizes thereby operating relay 105 as already described. The energization of relay 105 in turn causes the successive energization of relays 144, 145 and 143 as previously described. As soon as relay 143 energizes, the circuit of relay 142 is opened at the right armature and back contact of relay 143 and relay 142 becomes deenergized. The connection between the trunk circuit and the monitor's set through the contacts 10 15 of key 160, and between the subscriber's set A and the monitor's set through the contacts of key 220, are broken respectively through the deenergization of relay 142 and the energization of relay 105, and the subscriber's line and the main exchange become connected together as when the subscriber A called the main exchange himself. Following the connection of the subscriber's line to the main exchange, the private branch 20 25 monitor may release keys 220 and 260. As soon as the conversation has terminated the connection is broken down and all apparatus restored in the manner previously described.

30 It will be obvious that any number of private branch exchange lines may be provided as desired, it only being necessary to duplicate the relays 105, 106 and 107 individual to each subscriber's line. Further, a number of interoffice trunk lines may be provided as desired, it only being necessary to duplicate relays 105, 105', etc., and to provide suitable circuits for the energization of a relay associated with each additional trunk 35 40 line in order to connect the calling lines thereto.

What is claimed is:

1. In a telephone system, subscribers' lines, a trunk circuit, a monitor's position, a pair of keys and a switchhook at the substation of each line, means responsive to the operation of one of said keys and the operation of said switchhook to connect the respective line to said trunk circuit, means responsive to the operation of the other of said keys and the operation of said switchhook to signal said monitor's position, and means controlled by said monitor to extend said line to said monitor's position.
2. In a telephone system, subscribers' lines, a link circuit, a trunk circuit, a monitor's position, a pair of keys and a switchhook at the substation of each line, means responsive to the operation of one of said keys and the operation of said switchhook to connect the respective line to said trunk circuit, means responsive to the operation of the other of said keys and the operation of said switchhook to signal said monitor's position, and means controlled by said monitor to calling a wanted one of

tor to extend said line to said link circuit and thence to a wanted line.

3. In a telephone system, subscribers' lines, a trunk circuit, a monitor's position, a pair of keys at the substation of each line, means responsive to the operation of one of said keys to connect the respective line to said trunk circuit, means responsive to the operation of the other of said keys to signal said monitor's position, and means associated with said trunk circuit to prevent the concurrent connection of more than one of said lines thereto.

4. In a telephone system, subscribers' lines, a trunk circuit, a monitor's position, a pair of keys at the substation of each line, means responsive to the operation of one of said keys to connect the respective line to said trunk circuit, means responsive to the operation of the other of said keys to signal said monitor's position, means under the control of said monitor to connect her position with said trunk line, and means associated with said trunk line for preventing the connection of a second subscriber's line thereto concurrently with the connection thereof to another subscriber's line or to said monitor's position.

5. In a telephone system, subscribers' lines, a trunk circuit, a monitor's position, a pair of keys at the substation of each line, means responsive to the operation of one of said keys to connect the respective line to said trunk circuit, means responsive to the operation of the other of said keys to signal said monitor's position, means under the control of said monitor to connect her position with said trunk line, and means for transmitting a busy signal to a subscriber's line or to said monitor's position upon an attempted connection to said trunk line when it is engaged.

6. In a telephone system, subscribers' lines terminating in a branch office, a trunk circuit incoming to said branch office from a main office, a monitor's position at the branch office, means responsive to a call incoming from the main office to signal said monitor and to extend a connection from said trunk circuit toward her position, and means effective immediately thereupon for rendering said trunk circuit busy whereby said subscribers' lines may not become connected to said trunk circuit through the initiation of calls on said lines.

7. In a telephone system, subscribers' lines terminating in a branch office, a trunk circuit incoming to said branch office from a main office, a monitor's position means responsive to a call incoming from the main office to signal said monitor, means controlled by said monitor to extend a connection from her position to said trunk line, means individual to each line and controlled by said monitor for calling a wanted one of

129 42

said lines, and a common transfer key for transferring the call incoming on said trunk circuit to said wanted line.

8. In a telephone system, subscribers' two-conductor lines, a trunk circuit, a link circuit, a monitor's position, a pair of keys at the substation of each line for grounding either sides thereof, means responsive to the operation of one of said keys to connect the respective line to said trunk circuit, means responsive to the operation of the other of said keys to signal said monitor's position, and means individual to each of said lines and under the control of said monitor for connecting said lines to either said monitor's position or to said link circuit.

9. In a telephone system, subscribers'

lines, a link circuit, a monitor's position, a signal for each of said lines at said monitor's position, means responsive to the initiation of a call on one of said lines for operating the signal thereof, means individual to each of said lines and under the control of said monitor for interconnecting said lines over said link circuit, and means in said link circuit operative in response to the termination of a conversation between two subscribers' lines over said link circuit for operating the signals of the respective lines.

In witness whereof, I hereunto subscribe my name this 10th day of September A. D., 1923.

LUCIEN DEVAUX.
